UNITED STATES PATENT OFFICE

CHARLES F. BERTSCHINGER, OF JAMAICA, NEW YORK, ASSIGNOR TO TIDE WATER OIL COMPANY, OF BAYONNE, NEW JERSEY, A CORPORATION OF NEW JERSEY

PROTECTED TANK ENTRANCE

Application filed December 15, 1927. Serial No. 240,221.

The object of the invention is to provide an improved device for protecting a tank entrance, and particularly a fill pipe of an underground storage tank, in a manner which guards against unauthorized filling, while permitting the contents of the tank to be gauged through the entrance. The objects include simplicity and economy of construction and installation, convenience in filling and gauging, security of anti-fraud protection, ease of sealing, and protection against entrance of water. One of the objects of the invention is to provide a construction which possesses special advantages for what are known as flush-type fill boxes, which are embedded in concrete in or alongside the roadway of run-in filling stations. Other features of the invention will be apparent to those skilled in the art.

To these ends the invention comprises certain features of construction, parts and combinations of parts which will be described hereinafter and more particularly pointed out in the claims.

In the drawings forming part hereof:

Fig. 1 is a vertical section through the complete device applied to the upper end of a fill pipe;

Fig. 2 is a similar view with the cover removed and a gauge stick partly inserted;

Fig. 3 is an elevation on a smaller scale, showing the box embedded in concrete at the ground level, and a portion of an underground tank, the pipe being broken out for most of its length;

Fig. 4 is a vertical section on the line 4—4 of Fig. 1;

Fig. 5 is a plan view of Fig. 2, with the gauge stick in section, and portions in the interior of the box broken away and in section;

Fig. 6 is a detail perspective view of the top of the ball container;

Fig. 7 is a cross-section on the line 7—7 of Fig. 4; and

Figs. 8 and 9 are perspective views of two parts of the locking means.

Fig. 3 illustrates a portion of a large underground tank 2, which may be understood to be the storage tank of a gasoline filling

station. A fill and gauge pipe 3 extends upward from the tank through the ground to a point near the surface.

A box or fitting 4 is screwed onto the upper end of the pipe and is embedded in concrete 5, flush with the surface thereof. The box has an internally screw-threaded top entrance 6 into which a stout screw-threaded cover 7 is screwed flush with the top of the box, the latter having a lateral flange 8 with a rim 9, and the cover having a lateral flange 10 which lies within the rim. A gasket 110 is placed on the flange 8 beneath the flange 10 to form a tight joint when the box is closed.

The box affords a comparatively wide chamber 11 beneath the cover, this chamber having a lower portion 12 of somewhat smaller diameter, and there being an upwardly facing shoulder 13 between this recess 12 and the internally screw-threaded bore 14 of the box which engages the screw thread on the pipe. Under the entrance 6 there is an overhang 15, at the top of the chamber 11.

This is a standard form of box, and it is one of the advantages of the invention that it is adapted for incorporation in and combination with existing boxes, but it will be understood that the invention is not limited to this, and that the box, fitting or enclosure employed may be of special construction, or of different construction from that illustrated.

A hollow ball container 16 is dropped loosely into the lower part of the chamber of the box, which it approximately fits. This container has a top flange or external enlargement 17 which rests on the shoulder 13, and the remainder of the container may extend downward within the upper end of the pipe 3 when the box is applied thereto. A gasket 18 is interposed between the shoulder 13 and flange 17. This shoulder is, therefore, utilized not only to support the ball container but for the obtaining of a liquid tight joint at this region, to prevent any water or gasoline which may enter or be introduced into the box passing around the ball container and entering the tank through the pipe. The ball container 16 is in the form of a

small box having permanent walls, and its interior constitutes a ball chamber 19 containing a solid metal ball 20 smaller than the width of the chamber. Openings 21 and 22 are provided in the upper and lower walls 23 and 24 of the ball chamber, these openings being approximately in line one above the other, though somewhat offset with respect to each other, and being eccentrically disposed, toward one side of the chamber, as in my co-pending application Serial No. 215,552, filed August 26, 1927. The edge 25 of the lower opening forms a valve seat for the ball, which normally rests partly within this opening so as to prevent liquid from entering the pipe and tank by way of the interior of the ball container.

The chamber 19 is large enough to accommodate the ball 20 when the latter is pushed out of and aside from the opening 22 sufficiently to permit the introduction of a gauge stick 26, the lower end of the latter being tapered to a point at one side, at 26', for dislodging and camming aside the ball.

The bottom of the chamber 19 is sufficiently sloped so that the ball automatically returns into the opening 22 when the gauge stick is withdrawn. Or the result can be accomplished in substantially the same way by properly proportioning the ball in relation to the width of the space in the chamber 19 at one side of the hole, so that, with the stick in place the side wall of the chamber prevents the ball from being pushed aside from a position in which its center of gravity is over the edge of the hole.

The openings 21 and 22, with the interior part 16, form part of a through way for the passage of a gauge member through the pipe into the tank; and as in my said application the upper opening 21 is made of odd shape and restricted effective area, so as to make it practically impossible to fill into the tank fraudulently by inserting a nozzle in the opening, even assuming that the ball could be displaced by such a nozzle or in some other way, which would be difficult. Any liquid introduced into the chamber 11 above the part 16 is retained there, being prevented by the ball from passing through the interior of the part 19, and by the liquid tight joint at 18 from passing around the part. Even if the ball 20 did not seat liquid tight in the opening 22 it would not permit the passage of gasoline in any such quantities as to make fraudulent filling profitable; but to exclude water, which if present even in small amount in the gasoline is very detrimental, as well as to prevent fraudulent practices, it is highly important to provide liquid-tight joints or closures against passage of liquid through as well as around the part 16. Water may enter the box when the cover 7 is off or if the cover is not screwed tight, or if the joint at 65 110 should become leaky.

I find that a very advantageous shape for the small upper opening 21, and for the corresponding cross-section of the stick 26 is that of a broad isosceles triangle, with insets on the sides. These insets form internal projections 27 on the sides of the opening 21 and grooves 28 in the sides of the stick. This construction affords ample strength in the stick, with a sufficiently wide reading face 29 to receive the graduations and gallon numbers, and affords very adequate security against the introduction of a nozzle.

The top wall 23 of the ball container may be made of a separate piece from the body of the container as shown, but it is to be understood as being secured permanently or semi-permanently, so that the ball can not be lost and can not be taken out, except possibly as a matter of repair.

The part 16 constitutes an embodiment of a removable filling obstructor and gauge receiver. In respect to the ball and ball chamber, the provisions for the passage of the gauge stick, the nature of the stick and other matters and combinations involved therewith, the invention presents an improvement upon and within my copending applications Serial No. 111,942, filed May 27, 1926 and Serial No. 215,552, filed Aug. 26, 1927. As in those applications means are provided for locking or securing this part against unauthorized removal, preferably by means of a seal which must be broken or destroyed before the part can be removed, so that visible indication is afforded if the tank entrance has been tampered with. The representative of the oil company, authorized to fill the tank, is provided with seals and a suitable tool for re-sealing the tank after he has filled it.

One part of the present invention relates to an improved construction and disposition of locking means suited for the type of fill box indicated. It is more specifically a locking means which is secured by a seal, but I do not necessarily limit myself to a seal lock as to all aspects of the invention. Nor as to the particular locking or sealing features do I necessarily limit myself to a ball containing device as the filling obstructor and gauge receiver. In some cases the ball might be omitted and reliance placed upon the gauge opening through the part being sufficiently restricted or otherwise sufficiently obstructed to prevent unauthorized filling, or to discourage it by reason of the extreme slowness of the operation. Manifestly, however, it is much better to actually close a gauge opening in the obstructor by the ball, or possibly by some other automatic means. Another possibility is that the gauge member could be kept in the tank and pipe, and be prevented from removal from the filling obstructor, the opening through the obstructor being substantially filled by the gauge member, as in my Patent No. 1,604,874, dated October 26, 1926. 130

The locking means which I have here provided to prevent unauthorized removal of the filling obstructor and gauge receiver, or to prevent it without breaking a seal, which will indicate that the part has been removed, includes a removable cross-bar 31 which is disposed over the part 16 in the chamber 11 of the box 4, the ends of this cross-bar engaging beneath the overhang 15 in the upper part of the box. A screw 32 passes downward through a screw-threaded hole in the intermediate portion of the cross-bar and engages a socket or cup 33 on or in the top 23 of the part 16, the kerfed head of the screw being accommodated in a countersunk recess 34 in the bar. The screw is screwed down through the cross-bar against the part 16 and by reaction jams the ends of the cross-bar against the under surface of the overhang. This holds the part 16 firmly in place, and the interengagement of the screw with the socket 33 makes it impossible to pry the bar loose or to get it into a position where it might be taken out through the entrance 6. The socket 33 is preferably eccentrically disposed, and the bar when in position is consequently at one side of the center of the entrance 6. The bar is of such length that it can be taken out when the screw is screwed upward through the bar sufficiently to disengage the socket 33. The locking means when in place does not interfere in any way with the insertion of the gauge stick.

Means are provided for preventing unintended release of the screw 32, preferably by covering the head of the screw to prevent access thereto. For this purpose I preferably fit a sleeve 35 movably on the cross-bar, so as to cover and uncover the screw head. For greater security I contrive that the sleeve must be moved both lengthwise and rotatably in order to bring an opening 36 therein into position where it permits the screw to be unscrewed. An angular slot 37 in the sleeve is guided on the shank of the screw in this operation.

The sleeve or cover member is locked by a seal 38, the ribbon or wire of which is passed through openings in laterally projecting portions 39 and 40 on the bar 31 and sleeve 35, respectively. These portions are preferably so formed that the portion 39 is received within the portion 40 in the locked condition. When these parts are sealed together the opening 36 is out of register with the screw, and the head of the latter is covered by the wall of the sleeve.

In order to remove the part 16 for filling, the seal is broken, the sleeve 35 is shifted on the bar 31 to the position in which the point of a screw-driver can be inserted through the hole 36 into engagement with the kerf of the screw 32, the screw is unscrewed, the bar, with the screw and sleeve thereon, is taken out

through the entrance 6, and the part 16 is taken out.

While I have utilized the overhang 15 existing in a present standard form of fill box, it will be understood that in a specially constructed box this overhang may be replaced by other suitable downwardly facing surfaces or abutments, or by recesses or keeper sockets, beneath which or with which the ends of a locking device extending across a part such as the part 16 may engage.

In the locked condition, the reaction of the locking device between the part 16 and the overhang 15 also serves to apply pressure to the joint at 13 so as to hold the same perfectly tight.

While a screw in connection with a cross-bar is preferred as the means for creating downward pressure on the part 16 and for holding this part in place, the locking device might be made of relatively movable parts of specifically different construction for performing the same functions.

Other modifications and specifically different embodiments of the features of the invention will suggest themselves to the skilled mechanician. While the invention is particularly applicable to the pipes leading to underground tanks, features of the invention may be employed for guarding the entrances of tanks of other kinds or in other locations.

I claim:

1. A device of the character described, comprising a box adapted to be applied to the upper end of a pipe extending upward from an underground tank, a removable ball container inside said box, said ball container containing a ball chamber having openings for the passage of a gauge member, with a ball guarding the lower of said openings, and a locking device interposed between said ball container and a portion of the interior of the box above the container.

2. A device of the character described, comprising a box adapted to be applied to the upper end of a pipe extending upward from an underground tank, a removable ball container inside said box, said ball container containing a ball chamber having openings for the passage of a gauge member, with a ball guarding the lower of said openings, means between said ball container and a lower portion of the box to form a liquid-tight joint, and a locking device interposed between said ball container and a portion of the box to prevent unauthorized removal of the ball container, said locking device constructed to react between said ball container and a portion of the box so as to apply pressure to said joint.

3. Means for guarding a tank entrance, comprising a box adapted to be applied to the upper end of a pipe extending upward from an underground tank, said box provided with a closure, a removable filling ob-

5 structor in the box beneath said closure providing a passageway for a gauge member into the interior of the tank, and an interposed locking device adapted to prevent unauthorized removal of the obstructor, said locking device including a screw, and sealed means preventing access to the head of said screw for releasing the locking device.

10 4. Means for guarding a tank entrance, comprising a box, a removable filling obstructor in the box providing a passageway for a gauge member, and an interposed locking device adapted to prevent unauthorized removal of the obstructor, said locking device including a screw, a movable member for covering the head of the screw, and means for sealing said movable member.

15 5. Means for guarding a tank entrance, comprising a box, a removable filling obstructor in the box providing a passageway for a gauge member, and an interposed locking device adapted to prevent unauthorized removal of the obstructor, said locking device comprising a bar, a screw in said bar to coact with the obstructor, and sealed means covering the head of said screw.

20 6. Means for guarding a tank entrance, comprising a box, a removable filling obstructor in the box providing a passageway for a gauge member, and an interposed locking device adapted to prevent unauthorized removal of the obstructor, said locking device comprising a bar, a screw in said bar to coact with the obstructor, and a member carried by said bar and movable relatively thereto to cover and uncover the head of said screw.

25 7. Means for guarding a tank entrance, comprising a box, a removable filling obstructor in the box providing a passageway for a gauge member, and an interposed locking device adapted to prevent unauthorized removal of the obstructor, said locking device comprising a bar, a screw in said bar to coact with the obstructor, a member carried by said bar and movable relatively thereto to cover and uncover the head of said screw, and means for securement of said member by means of a seal.

30 8. Means for guarding a tank entrance, comprising a box, a removable filling obstructor in the box providing a passageway for a gauge member, and an interposed locking device adapted to prevent unauthorized removal of the obstructor, said locking device comprising a bar, a screw in said bar to coact with the obstructor, and a sleeve movable on said bar to cover and uncover the head of said screw.

35 9. Means for guarding a tank entrance, comprising a box, a removable filling obstructor in the box providing a passageway for a gauge member, and an interposed locking device adapted to prevent unauthorized removal of the obstructor, said locking device comprising a bar, a screw in said bar to

40 coact with the obstructor, a sleeve movable longitudinally and rotatably on said bar and having an opening adapted to be brought into register with the head of the screw, and portions on said bar and sleeve through which to pass a sealing element.

45 10. Means for guarding a tank entrance, comprising a box, a removable filling obstructor in the box providing a passageway for a gauge member, and an interposed locking device adapted to prevent unauthorized removal of the obstructor, said locking device comprising a bar, a screw in said bar to coact with the obstructor, a sleeve movable longitudinally and rotatably on said bar and having an angular slot guided on the lower portion of the screw and an opening adapted to be brought into register with the head of the screw, and portions on said bar and sleeve through which to pass a sealing element.

50 11. Means for guarding a tank entrance, comprising a box, a removable filling obstructor in the box providing a passageway for a gauge member, and an interposed locking device adapted to prevent unauthorized removal of the obstructor, said locking device comprising a bar, a screw in said bar to coact with the obstructor, and a sleeve movable on said bar to cover and uncover the head of said screw, said sleeve and bar having portions adapted to be received one inside the other and formed with openings for the passage of a sealing element.

55 12. A device of the character described, comprising a box adapted to be applied to the upper end of a pipe extending upward from an underground tank, a cover for said box, a removable ball container inside said box, said ball container containing a ball chamber having openings for the passage of a gauge member, with a ball guarding the lower of said openings, and a locking device to prevent unauthorized removal of said ball container from said box when said cover is removed.

60 13. A device of the character described, comprising a box adapted to be applied to the upper end of a pipe extending upward from an underground tank, a cover for said box, a removable ball container inside said box, said ball container containing a ball chamber having openings for the passage of a gauge member, with a ball guarding the lower of said openings, and a locking device interposed between said ball container and a portion of the interior of the box.

CHARLES F. BERTSCHINGER.

CERTIFICATE OF CORRECTION.

Patent No. 1,773,295.

Granted August 19, 1930, to

CHARLES F. BERTSCHINGER.

It is hereby certified that the above numbered patent was erroneously issued to "Tide Water Oil Company", as assignee of the entire interest in said invention, whereas said patent should have been issued to the inventor, said "Bertschinger, and Tide Water Oil Company", said company being assignee of three-fourths interest only in said invention, as shown by the records of assignments in this office; and that the said Letters Patent should be read with this correction therein that the same may conform to the record of the case in the Patent Office.

Signed and sealed this 23rd day of September, A. D. 1930.

(Seal)

**M. J. Moore,
Acting Commissioner of Patents.**
